(57) **CLAIM**

The ornamental design for protective cover for a tablet computer, as shown and described.

DESCRIPTION

FIG. 1 is a perspective view of a protective cover for a tablet computer showing our new design in a closed configuration; FIG. 2 is a second perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a perspective view thereof shown in an open configuration;

FIG. 10 is a second perspective view of the open configuration;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side elevation view thereof; and,

FIG. 16 is a right side elevation view thereof.

The broken lines represent environment that forms no part of the claim.

1 Claim, 9 Drawing Sheets
